UNITED STATES PATENT OFFICE.

JAMES S. BIRCH, OF CHICAGO, ILLINOIS.

JOIST SUPPORT.

Application filed October 5, 1925. Serial No. 60,386.

To all whom it may concern:

Be it known that I, JAMES S. BIRCH, a citizen of the United States, and a resident of the city of Chicago, in the county of Cook and State of Illinois, have invented certain new and useful Improvements in a Joist Support; and I do hereby declare that the following is a full, clear, and exact description of the same, reference being had 10 to the accompanying drawings, and to the numerals of reference marked thereon, which form a part of this specification.

In laying concrete floors in steel structures it has been the custom to first support beam forms in position around the horizontal I-beams, after which the joists for supporting the concrete floor forms are mounted in position upon supports which are built up upon the outer sides of the beam forms 20 thereby requiring extensive carpentry work, all of which must afterwards be ripped out.

This invention relates to improved steel supports for the supporting joists upon which floor forms are supported, said joist supports adapted to be readily engaged upon the upper flange of an I-beam forming a part of the steel structure of a building, thereby obviating the expensive temporary structural frame work supports 30 which have heretofore been used to support the joists below floor forms.

It is an object of this invention to provide an improved steel joist support adapted to be readily engaged in position on the upper 35 portion of an I-beam to afford looped hangers in which the supporting joists of a concrete floor form may be engaged.

It is also an object of this invention to provide a double joist support adapted to be engaged upon the upper flange of an I-beam above a beam form to afford looped hangers or supports in which the supporting joists 40 of a floor form may be removably engaged with the ends of said joists abutting against the sides of the beam form in a rigid position, without requiring the use of nails and expensive carpentry work.

It is an important object of this invention to provide a simplified form of support for 50 the supporting joists of a floor form, said support comprising a pair of interfitting hangers having members forming a part thereof which are adapted to be clamped against opposite sides of the upper flange of a structural I-beam to hold the hangers in a 55 position overhanging the side walls of a

concrete beam form enclosing the lower portion of the structural I-beam.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary plan view of a portion of a floor under construction illustrating a plurality of joist supports engaged in position on a pair of structure 70 I-beams for supporting the joists upon which the floor forms are supported.

Figure 2 is a fragmentary vertical detail section taken on line II—II of Figure 1.

Figure 3 is a fragmentary sectional view 75 taken on line III—III of Figure 1.

Figure 4 is an enlarged fragmentary detail section taken on line IV—IV of Figure 3.

As shown on the drawings:

The reference numeral 1 indicates a horizontal I-beam forming a part of the structural work of a building under construction. Surrounding the lower portion of the I-beam 1 is a wooden beam form comprising a bottom 2 and side walls 3. The beam form is 80 adapted to be supported in position by any suitable means to permit concrete to be poured into the open upper portion of the beam form and around the I-beam.

For the purpose of supporting a wooden 90 floor form 4 in position between a pair of the I-beams 1 a plurality of joists 5 are positioned between the I-beams in parallel relation to one another so that the floor form 4 may be constructed thereon. The ends of 95 the joists 5 abut against the outer sides of the side walls 3 of the beam form as clearly illustrated in Figure 2.

For the purpose of supporting the floor 100 form supporting joists 5 in position, improved metal joist supports are provided which cover the patentable features of this invention. The improved joist support comprises a pair of metal angle iron clamps 6, one flange of which is provided with two 105 pairs of apertures 7 and a pair of notches 8 alternately spaced with respect to the pairs of apertures 7. Connected to each of the angle iron clamps 6 is a steel metal U-shaped hanger or strap 9 constructed of a steel rod, 110 the arms of which project through the uppermost apertures of each of said pair of

- apertures 7 and are bent in the form of a loop at 10 and project back inwardly through the lowermost apertures 7 with the ends 11 resting upon the inner face of the lower flange of the angle iron clamps 6 as clearly illustrated in Figure 4. It will thus be seen that the hook ends 10-11 of the hangers 9 are engaged through the apertured flange of an angle iron clamp 6 so that the angle iron clamp 6 may be engaged against one longitudinal edge of the upper flange of the I-beam 1 with the lower flange of the angle iron clamped below the lower inclined surface of the upper I-beam flange and separated therefrom by the terminals 11 of the hook members 10-11. The two arms of each hanger project transversely across the top of the upper flange of the I-beam 1 and are then bent downwardly at an angle as illustrated in Figure 2 with the loop portion of the hanger directed downwardly to the outside of the outer surface of one side wall 3 of the beam form 2-3. A second angle iron clamp 6 is engaged on the opposite side of the top flange of the I-beam 1 with the hanger extending transversely across the top of the I-beam and then downwardly at an angle to position the looped end of the hanger 9 to the outside of the opposite side of the beam form 2-3. The notches 8 provided in the angle iron clamps 6 are positioned to receive the arms of a coacting joist support member seated therein as illustrated in Figures 1 and 3.
- 35 The joist support as illustrated and described comprises a pair of units, each of which embraces an angle iron clamp 6 and a hanger 9, with the arms of one hanger adapted to seat in the notches of the angle iron clamp of a coacting joist support unit. The two joist support units are positioned upon the upper flange of the I-beam 1 with the iron clamps on opposite sides of said flange, thereby permitting the arms of the hangers to project transversely across the top of the beam flange, with the angle iron clamps clamped adjacent the longitudinal edges of the top flange of the I-beam. The joist support units may thus be easily clamped in position upon the top flange of an I-beam with the two hangers projecting downwardly upon opposite sides of the I-beam and to the outside of the side walls 3 of the beam form 2-3.
- 50 With a plurality of sets of joist supports clamped in position as illustrated in Figure 1 upon the upper flanges of a pair of parallel I-beams, the hangers 9 are so positioned that a supporting joist 5 may be seated in a pair of oppositely disposed hangers to span the space between the adjacent side walls of a pair of beam forms 2-3 supported in position around the lower portions of the two parallel I-beams. Of course, any 60 number of joist supports may be engaged on the I-beams so that a plurality of joists 5 may be readily placed in position between a pair of parallel beam forms with the ends of the joists abutting against the side walls of said beam forms. After a plurality of 70 joists 5 have been supported in parallel relation between a pair of I-beams, a support is provided upon which the wooden floor form 4 for a concrete floor may be readily supported upon the joists 5 between the wooden beam forms 2-3 thereby completing the wooden forms necessary for the proper construction of concrete beams and floor sections. After the concrete has been poured to form the beams and floor and the concrete 80 has been permitted to set, the beam forms 2-3 may be removed from below after which the arms of the hangers 9 may be cut below the floor forms 4 thereby permitting the supporting joists 5 and the floor forms 4 85 to be removed from beneath the concrete flooring. The angle clamps 6 and the upper portions of the hanger arms are of course embedded in the concrete flooring and remain in position to serve as reinforcing 90 members.
- 95 I am aware that many changes may be made, and numerous details of construction may be varied through a wide range without departing from the principles of this invention, and I therefore do not purpose limiting the patent granted hereon, otherwise than necessitated by the prior art.
- I claim as my invention:
1. A joist support for a concrete floor form, said joist support comprising a pair of angle clamps adapted to be engaged against opposite sides of the upper flange of an I-beam, said angle clamps having notches and apertures therein, and a pair of looped metal hangers, the arms of which are hooked and project through the apertures of said angle clamps with the arms of the hangers projecting transversely across the top of the I-beam and seated in the notches of the opposite angle clamp. 100
  2. A joist support for concrete floor forms and the like, said joist support comprising a pair of looped hangers, and a pair of apertured notched clamping members adapted to be clamped on the opposite sides of the upper flange of an I-beam with the arms of said hangers seated in the notches of said clamping members and the ends of said arms bent to project through the apertures of the 110 respective clamping members. 115
  3. A joist support for floor forms comprising a pair of clamping members having apertures and notches therein and adapted to be positioned on opposite sides of the top flange of an I-beam or the like, and a pair of hangers for receiving and supporting the joist supports of the floor forms, said hangers having the arms thereof seated in the notches of one of said clamping mem- 125 130

bers with the ends of said arms hooked and projecting through apertures in the other of said clamping members to hold the hangers in position with the arms thereof spanning the upper flange of the I-beam.

4. A joist support of the class described comprising a pair of looped metal hangers and a pair of clamping members having notches and apertures therein with the arms 10 of said hangers seated in said notches and lockingly engaged through said apertures.

5. A joist support for concrete floor forms, said support comprising a pair of units each embracing an angle clamp, one flange of 15 which is provided with a pair of notches and two pairs of apertures, and a U-shaped hanger, the arms of which are hook shaped and project through said pairs of apertures to permit the clamp to be set adjacent one 20 side of the upper flange of an I-beam with the flange of said I-beam engaged between the arms forming said hooked portions.

6. A joist support for floor forms and the like, said support comprising a pair of 25 looped metal hangers adapted to be positioned on opposite sides of an I-beam, of a

wooden beam form surrounding the lower portion of the structural I-beam, and a pair of notched clamping members engaged on the ends of said looped hangers adapted to 30 be clamped against opposite sides of the upper flange of the I-beam with the arms of said hangers projecting transversely across the top of the upper flange of the I-beam and seated in the notches formed in 35 said clamping members.

7. The combination with a steel structural member, of a beam form enclosing part of said member, floor forms positioned against the opposite sides of said beam form, 40 joists supporting said floor forms and abutting against the sides of said beam form, apertured metal clamps engaged on said steel structural member, and metal hangers connected with said clamps and projecting 45 across the top of said steel structural member in opposite directions and directed downwardly on opposite sides of said beam form to afford supports for said joists.

In testimony whereof I have hereunto sub- 50 scribed my name.

JAMES S. BIRCH.
